(57) **CLAIM**

The ornamental design for a brace, as shown and described.

DESCRIPTION

FIG. 1 is a top perspective view of a brace showing the new design;

FIG. 2 is a top plan view thereof;

FIG. 3 is a bottom plan view thereof;

FIG. 4 is a side elevation view thereof;

FIG. 5 is an opposite side elevation view thereof;

FIG. 6 is a front elevation view thereof; and,

FIG. 7 is a rear elevation view thereof.

Any portion of the brace between the break lines forms no part of the claimed design.
